UNITED STATES PATENT OFFICE.

JAMES C. STINSON, OF BRADFORD, PENNSYLVANIA.

DEEP-WELL PACKER.

1,177,971.

Specification of Letters Patent.

Patented Apr. 4, 1916.

Application filed March 29, 1915. Serial No. 17,745.

To all whom it may concern:

Be it known that I, JAMES C. STINSON, a citizen of the United States, residing at Bradford, in the county of McKean and State of Pennsylvania, have invented certain new and useful Improvements in Deep-Well Packers, of which the following is a specification.

This invention relates to deep-well packers, and has for its object the provision of a deep-well packer in which the construction and operation of the devices for this purpose will be simplified, while the efficiency of the same will be increased.

15 The invention is illustrated in the accompanying drawings and consists in certain novel features which will be hereinafter first fully described and then more particularly pointed out in the appended claims.

20 In the drawings: Figure 1 is an elevation of a deep-well packer embodying my present improvements; and Fig. 2 is a vertical section of the same.

In the accompanying drawings, the reference numeral 1 indicates the packer which is the usual elastic cylinder or sleeve fitted around the casing 2 between an upper fixed collar 3 thereon and a lower loosely mounted collar or expander 4. The expander is fitted 25 upon the casing in contact with the lower end of the packer and has its lower end tapered, as indicated at 5, whereby it may be engaged by the upper ends of the slips 6 so as to throw the said slips outwardly into 30 engagement with the wall of the well and thereby anchor the slips and slip cage so that further downward movement of the casing will expand the packer tightly against the wall of the well in the usual manner.

40 In carrying out the present invention, the slip cage 7 is provided at diametrically opposite points with bayonet slots 8 having long vertical branches and short horizontal branches at their upper ends, and the casing 45 is provided at diametrically opposite points with pins 9 adapted to engage said bayonet slots, it being readily understood that the pins are inserted through the slots into the casing after the cage has been placed in position upon the casing. The cage is also provided at diametrically opposite points with openings 10, said openings being located between the bayonet slots and approximately in the horizontal plane of the lower ends of 55 said slots. The casing is also provided with diametrically opposite openings which reg-

ister with the said openings 10 and receive the ends of a telescopic or other sustaining pin 11 on a packer disk 12.

In the upper end of the slip cage 7, I 60 form notches or recesses 13 which receive the lower ends of the slips 6 and leaf springs 14 are fitted against the outer surfaces of the cage and the slips so as to bridge the joint between them and have their upper 65 and lower ends respectively secured to the slips and the cage. The slips are thus normally held to the casing but are yieldably mounted so that they may be forced outwardly into engagement with the wall of 70 the well so as to anchor the device, and to increase the efficiency and certainty of the anchoring operation the upper ends of the slips on their outer faces are preferably serrated, as indicated at 15. It will be readily 75 noted that the slips are reduced in width below the upper serrated portions thereof, and these reduced portions are engaged by the lateral lugs or lips 16 on the sides of the bowed leaf springs 17 near the upper ends 80 of the said springs. The lower ends of these springs 17 are rigidly secured to the slip cage 7, as clearly shown, and the intermediate portions thereof are bowed sufficiently 85 to frictionally engage the wall of the well and thereby hold the cage against downward movement after it has been released from the casing.

It will be readily seen from the foregoing description, taken in connection with the 90 accompanying drawings, that I have provided a packer which may be utilized as a disk packer or as a hook packer.

When the device is utilized as a disk packer, the pins 11 of the disk 12 are engaged in the registering openings of the casing and the cage and the pins 9 on the casing are located at the upper ends of the bayonet slots and immediately over the vertical portions of said slots. When the device 100 has reached the point at which it is to be anchored, a weight is dropped through the casing in the usual manner so as to break or release the disk whereupon the casing, being freed of the cage, will move downwardly 105 relative to the cage so that the lower tapered end of the expander 4 will be carried down within the upper ends of the slips and force the same outwardly into the wall of the well thereby anchoring the slips and the slip cage so that the continued downward movement of the casing will cause the fixed collar 110

3 to compress the packer between itself and the expander ring or collar in the usual manner. The vertical portion of the slots 8 should be long enough to permit the complete radial expansion of the packer before further downward movement of the casing is arrested through contact of the pins 9 with the lower ends of the slots thereby avoiding premature stoppage of the casing 10 and inefficient packing.

If it be preferred to use the device as a hook packer, the disk is not inserted in place and the pins 9 are disposed at the closed ends of the horizontal portions of the bayonet slots 8 as indicated in Fig. 1. Then, when the device reaches the point where it is to be anchored, the casing is partly rotated so as to bring the pins 9 over the vertical portions of the bayonet slots whereby 15 the operation previously described may be performed.

It will be readily seen that I have provided a device which is exceedingly simple in the construction and arrangement of its parts and is not liable to get out of order. The slips are held to the casing and to the expander ring by two sets of springs so that the engagement of the slips in the wall of the well before the desired point has been 20 reached is not apt to occur. The springs 14 which connect the slips and the cage are disposed under and protected by the bowed springs and are, therefore, not liable to be injured in the descent of the device. Moreover, the strain upon the bowed springs is 25 reduced inasmuch as they may be bowed to a greater extent and are not called upon to exert the same holding force upon the slips. At the same time, the compression of 30 the bowed springs tends to prevent lateral 35

movement of the slips transversely to the springs and thereby serves to hold the slips in their proper operative positions.

Having thus described the invention, what is claimed as new is:—

1. In a well packer, the combination of a slip cage, slips disposed at the upper end of the cage, and leaf springs having their upper ends secured to the outer surfaces of the slips and their lower ends secured to 50 the outer surface of the cage.

2. In a well packer, the combination of a slip cage, slips disposed at the upper end of the cage, leaf springs secured to the cage and the respective slips, and bowed springs 55 secured to the cage and projecting upwardly therefrom and having their upper ends provided with lateral lips engaging the sides of the slips.

3. In a well packer, the combination of a slip cage, slips mounted on the upper end of the cage for relative swinging movement, and bowed springs secured to the cage and having their upper ends provided 60 with lateral lips engaging the side edges 65 of the slips.

4. In a well packer, the combination of a slip cage having recesses in its upper edge, slips having their lower ends fitted in said recesses, springs secured to the cage and the slips, and other springs secured to the cage over the first-mentioned springs and having their upper ends freely engaging the 70 slips.

In testimony whereof I affix my signature in presence of two witnesses.

JAMES C. STINSON. [L.S.]

Witnesses:

JAMES GEORGE,
JOHN BIRD.
